UNITED STATES PATENT OFFICE.

BASIL WALTER BRIDGE PUCKLE, OF TWYFORD, ENGLAND.

VARIABLE-SPEED GEAR.

1,329,476.

Specification of Letters Patent.

Patented Feb. 3, 1920.

Application filed December 5, 1918. Serial No. 265,839.

To all whom it may concern:

Be it known that I, BASIL WALTER BRIDGE PUCKLE, a subject of the King of England, residing at Twyford, in Berkshire, England, have invented certain new and useful Improvements in Variable-Speed Gears, of which the following is a specification.

This invention relates to variable speed gears and has for its object to provide a system of gear-changing mechanism involving pull-rods so arranged as always to be under tension while effecting the gear-changing operations.

The invention is applied to variable speed gears of the type having sliding gear-wheels and consists in the combination with each sliding gear-wheel, of a pull-rod for operating it, a single control-member and means for selectively connecting the control-member to either end of the pull-rod whereby the rod is put in tension when the control-member moves the wheel in either direction. In the preferred construction there are provided for each gear-wheel, a pair of rods arranged side by side and whereof one directly operates the gear-wheel, means for selectively connecting the control-member to one end of either of the rods to pull it, and means operatively connecting together their other ends in such manner that when one is pulled by the control-member, it pulls the other in the opposite direction.

Other features of the invention will also be described with reference to the accompanying drawing which illustrates a convenient method of carrying the invention into effect.

The figures are diagrammatic, and, in preparing them, parts not required to illustrate the invention have, in general, been omitted.

Figure 1 is a side elevation of the gear.

Fig. 2 is a plan of the same.

Fig. 3 is a section on the line AB of Fig.

45 2 with some parts broken away.

a is the engine-shaft which can be coupled to the intermediate shaft a' by the cone-clutch c. The driven shaft b carries two sliding gear-wheels d, e which are arranged to be slid along the shaft by engaging members or yoke-pieces f, g which engage respectively with channelled collars 45, 46 connected to, or formed integrally with, the gear-wheels d and e. There are two pairs 50 of pull-rods, namely the pair j, k which are

associated with the gear-wheel d, and the pair m, n which are associated with the gear-wheel e. The yoke-piece f is fixed on the rod j, and the yoke-piece g is fixed on the rod m. p is a control-member or lever pivoted on an axle q. This control-lever, which is preferably made in the form a foot-pedal, serves to actuate the pull-rods and so to shift the gears. It also acts to open and close the cone-clutch c.

r, s are parallel vertical plates mounted on opposite sides of the control-lever and with upper surfaces formed as arcs of circles whose centers coincide with the axis of the lever axle q. Four L-shaped slots t, u, v, w, are formed in each of these plates, the slots in the one plate being opposite, and similar to, the slots in the other respectively. Each of the pull-rods has rigidly secured on it a pick-up finger, the fingers being indicated by the reference numerals 2, 3, 4, 5 respectively. These fingers are formed with small horizontal portions at their upper ends, which portions enter the slots in the plates r, s. The arrangement shown in the drawing is a convenient one; two of the fingers engage with the one plate and two of the fingers with the other plate, one finger in each case being on the inside, and the other on the outside, of the plate. The control-lever is made in two parts 6, 7, the upper part 6 being arranged to have a telescopic sliding connection with the lower portion 7. This upper portion is provided with a transverse pin x extending on both sides of the lever. This pin is adapted to enter any one of the four slots in the plates r, s and to engage with the pick-up finger in that slot in one or other of the plates. The telescopic action of the upper part of the lever, combined with the swinging-over of the lever, allows the pin x to be moved down the vertical part of the slot and along the horizontal portion. The pin x therefore acts as a selecting finger whereby any one of the 100 pick-up fingers can be engaged and moved along its slot. It follows that, by suitable action of the lever, any one of the pick-up fingers can be actuated, and consequently any one of the pull-rods can be mechanically 105 put in tension and moved to the left in Fig. 1.

By swinging the lever toward the left, the cam y on the bottom of the lever acts on a collar z to disengage the cone-clutch c 110

and thus disconnect the intermediate shaft from the engine-shaft.

Each pull-rod is provided with a toothed rack 11, 12, 13 and 14 respectively. The 5 racks 11 and 12 face each other and gear with a common pinion 15 which is pivoted to the fixed frame or box which carries the gear. It follows that, when either of the racks 11 or 12 is pulled to the left (in Fig. 1) 10 by its pull-rod, the opposing rack will be driven to the right an equal distance. The racks 13, 14 and the pinion 16 are similarly arranged and act similarly.

The two pairs of pull-rods are interconnected by rocking levers 17, 18 which are pivoted at their centers to the frame or gearbox, the ends of the levers being provided with slots 19 within which are located pins 20 carried by blocks 21, 22, 23 and 24. The 20 blocks 21 and 24 are fixed on the pull-rods *j* and *m* respectively, but the blocks 22 and 23 are loose and slideable respectively on the same rods. In consequence of this, it follows that, when the block 21 is moved by its 25 pull-rod in either direction, the block 23 is slid along its pull-rod *m* in the opposite direction: and, similarly, when the block 24 is moved in either direction by its pull-rod *m*, the block 22 is slide along its pull-rod *j* 30 in the opposite direction.

25 is a tie-rod fixed to the yoke-piece *g* and extending through the other yoke-piece *f*. It carries stops 26, 26^a, one on each side of the yoke-piece *f* to limit the relative movement of the two yoke-pieces as hereinafter described.

27 is a lay shaft on which are fixed the gear-wheels 28, 29, 31 and 32. 33 is a short idle shaft or stud which carries the reversing gear-wheel 34 which is constantly in mesh with the gear 32. 35 is a gear-wheel which is fixed on the intermediate shaft *a'* and is constantly in mesh with the gear-wheel 28.

45 Fixed to the intermediate shaft *a'* or to the pinion 35 (which is fastened to this shaft) is one portion 42 of a dog-clutch, the other portion 43 of which is fixed to, and moves with, the gear-wheel *d*. The movement of the gear-wheel *d* to the left therefore puts the clutch in engagement, and the reverse movement given to this gear-wheel takes the clutch out of action.

To bring all the racks simultaneously into 55 the neutral position when desired a cross-bar 39 is employed, which bar is disposed behind the racks and is connected by tie-rods 37, 38 to another cross-bar 36 disposed in front of the control-lever. The rods 37, 60 38 are mounted in any convenient manner so that they can slide, and are provided with stops, for example the collars 37*, 38* respectively for butting against fixed guide-pieces 44* which also serve as abutments for 65 spring 44. The springs, by reason of the

stops 37*, 38*, normally keep the cross-bar 39 in the position shown in the drawings, and in this position the cross-bar 36 is sufficiently forward to clear the control-lever when in any one of its positions for operating the 70 gears. To bring all of the gears simultaneously to the neutral positions the lever is swung forward beyond the position for engaging the pick-up finger 5 so that it is brought into contact with the cross-bar 36 75 and thus advances the cross-bar 39, which in turn pushes back any one or more of the racks which may have been moved rearwardly, whereby all the racks are brought into the position shown in Fig. 2.

To put in the top speed, the control-lever is swung forward until the selecting finger *a* enters the slot *t*. Making use of the telescopic action of the lever, the driver forces the selecting finger down the vertical portion 85 of the slot and along the horizontal portion until it engages with the pick-up finger 2 so as to push this finger to the left and put tension on the pull-rod *j*. This causes the yoke-piece *f* to move the gear-wheel *d* to the left and close the dog-clutch 42, 43. The driven shaft *b* is then engaged for direct drive by the intermediate shaft, but the swinging-forward of the control-lever has disengaged the cone-clutch *c* previous to the closing of 95 the dog-clutch. The control-lever is now swung back so as to engage the cone-clutch and thus bring the direct drive into operation from the engine-shaft through the intermediate shaft to the driven shaft.

The movement of the pull-rod *j* to the left carries the block 21 (which is fast on the pull-rod) and that end of the lever 17 to the left, and the other end of this lever, acting on the block 23, which is loose on its pull-rod, moves this block over to the right up against the block 24. As this block 24 is fixed on its pull-rod, and the yoke-piece *g* is also fixed on the same pull-rod *m*, the gear wheel *e* is prevented from moving to the left. 105 Moreover, the movement of the yoke-piece *f* to the left, as already mentioned, brings it up against the stop 26 on the tie-rod 25, and this tie-rod consequently prevents the yoke-piece *g* from moving to the right. The 110 yoke-piece *g*, and the gear-wheel *e* are thus locked against movement in either direction, and the gear-wheel *e* cannot engage either with the pinion 31 or the pinion 34 while the dog-clutch 42, 43 is in operative position.

If it is now desired to throw in the second gear, the control-lever is swung forward, and its selecting finger is entered into, and moved along, the slot *u*. By this action 125 the cone-clutch is opened, and the pick-up finger 3, fixed on the pull-rod *k*, is engaged. This rod is consequently pulled to the left, which motion, through the agency of the racks and pinion, pulls the rod *j* to the right 130.

so as to open the dog-clutch 42, 43 and thereafter, to bring the gear-wheel *d* into meshing position with the pinion 29. On the swinging-back of the control-lever, the cone-clutch *c* is closed, and the shaft *b* is consequently driven through the gear-wheels 35, 28 and 29, *d*.

The movement of the rod *j* to the right, as just mentioned, brings the block 21 up 10 against the block 22 and consequently holds the adjacent end of the lever 18 against movement to the left. The other end of the lever is consequently restrained from movement to the right and, as the block 24 and 15 the yoke-piece *g* are both fast on the rod *m*, the gear-wheel *e* is restrained from movement to the right, (which might cause it to engage with the reversing pinion 34) while movement to the left (which might 20 cause it to engage with the pinion 31) is prevented by the engagement of the stop 26^a with the yoke-piece *f*.

If it is now desired to employ the third speed, the selecting finger of the control-lever is entered into the slot *v*, and the pick-up finger 4 is actuated to move the rod *m* to the left, the control-lever at the same time opening the cone-clutch *c*. The yoke-piece *g* is consequently pulled to the left and 30 places the gear-wheel *e* in mesh with the pinion 31. The control-lever 6 being now swung back, the cone-clutch *c* is closed, and the shaft *b* is driven through the gear-wheels 35, 28 and 31, *e*.

The movement of the rod *m* to the left, as 35 just mentioned, brings the block 24, which is fast on the rod *m*, up against the loose block 23 and thus restrains the adjacent end of the lever 17 from movement to the right.

The other end of this lever is thus prevented 40 from movement to the left, and consequently the yoke-piece *f* prevents a movement of the gear-wheel *d* which would close the dog-clutch 42, 43. A movement of the gear-wheel *d* to the right is prevented by the stop 45 26^a on the tie-rod 25.

If it is now desired to put the reversing gear into operation, the control-lever is 50 swung forward, the selecting finger entered into the slot *w*, and the pick-up finger 5 is actuated to move the rod *n* to the left, the control-lever at the same time opening the cone-clutch *c*. Through the action of the racks and pinion, the rod *m* is pulled to the 55 right, and consequently the yoke-piece *g* moves the gear-wheel *e* into mesh with the reversing pinion 34 which is constantly in mesh with the pinion 32. The swinging-back of the control-lever, by closing the cone-clutch, causes the shaft *b* to be driven 60 in a reverse direction through the gear-wheels 35, 28 and 32, 34, *e*.

The movement of the block 24 (which is 65 fast on the rod *m*) to the right swings over the remote end of the lever 18 to the left up

against the block 21 and consequently prevents the movement of the yoke-piece *f* to the right and thus restrains the gear-wheel *d* from meshing with the gear-pinion 29. Moreover, as the tie-rod 25 has been moved 70 to the right with the yoke-piece *g* until the stop 26 is up against the yoke-piece *f*, the latter is restrained from movement to the left, and consequently the dog-clutch 42, 43 can not be closed.

Either of the gear-wheels *d* and *e*, after having been moved into operative position, may be retained in that position by a spring 75 detent or other suitable device.

When it is desired to place the gear in its 80 neutral position, that is, in the position shown on the drawing when neither the wheel *d* nor the wheel *e* is in gear with a pinion and when the dog-clutch 42, 43 is 85 open, the control-lever is swung forward till the selecting finger *x* passes beyond the slot *w*. The rods 37, 38 are thus moved to such an extent as to bring the cross-bar 39 up against any projecting racks and force these 90 racks to the left into the positions shown on the drawing.

As the control-lever can be made in the form of a foot-pedal, the employment of this gear arrangement obviates the necessity of the driver employing either of his hands 95 in shifting the gears. A driver can therefore, as a rule, give both hands to steering and other operations, while, in the case of a man who has only the use of one hand, this need never, as a rule, be taken off the steering wheel.

Only two slots are really necessary in each of the plates *r* and *s*; but it is convenient to have the one plate slotted exactly like the other, *i. e.* to have two idle slots in each plate, as allowing of a simpler construction or action of the control-lever and selecting finger.

What I claim as my invention and desire 105 to secure by Letters Patent is:—

1. In variable-speed gear comprising a 110 slideable change-speed member, the combination with the slideable change-speed member, of a pull-rod operatively engaged therewith at a point intermediate of its ends to impart sliding movement to the said member in opposite directions, and a control member arranged to mechanically impart tensile stress selectively to either end of the pull-rod to slide the said change-speed member, for the 115 purpose specified.

2. In variable-speed gear comprising a plurality of slideable change-speed members, the combination with the said members, of a plurality of pull-rods operatively engaged 120 at points intermediate of their ends one with each change-speed member to impart sliding movement to their allotted members, and a single control member for the pull-rods arranged to mechanically impart tensile 125 stress to the said members.

stress selectively to either end of each pull-rod for selectively sliding the change-speed members, for the purpose specified.

3. In a variable-speed gear comprising two slidable change-speed members, the combination with the two change-speed members, of a pair of pull-rods whereof the elements are arranged side-by-side, one rod being operatively connected with one of said members for sliding it when the rod is moved endwise, another pair of pull-rods disposed parallel to the first and having one rod operatively connected with the other of said members for sliding it when the rod is moved endwise, means operatively connecting the two rods of one pair at adjacent ends, means operatively connecting the two rods of the other pair at the corresponding adjacent ends, so that when one rod of either pair is pulled in one direction the other rod of the same pair is pulled in the reverse direction, and a single control member for the pull-rods arranged to selectively impart tensile stress to either of the other adjacent ends of either pair of the said pull-rods.

4. In a variable-speed gear comprising two slidable change-speed members, the combination with the two change-speed members, of a pair of pull-rods whereof the elements are arranged side-by-side, one rod being operatively connected with one of said members for sliding it when the rod is moved endwise, another pair of pull-rods disposed parallel to the first and having one rod operatively connected with the other of said members for sliding it when the rod is moved endwise, means operatively connecting the two rods of one pair at adjacent ends, means operatively connecting the two rods of the other pair at the corresponding adjacent ends, so that when one rod of either pair is pulled in one direction the other rod of the same pair is pulled in the reverse direction, a single control member for the pull-rods arranged to selectively impart tensile stress to either of the other adjacent ends of either pair of the said pull-rods, and locking means operatively connected with each pair of pull-rods and arranged to lock the one pair against movement when the other pair is operated.

5. In variable-speed gear comprising two slidable change-speed members, the combination with the two change-speed members, of a pair of pull-rods whereof the elements are arranged side-by-side, one rod carrying an operating member operatively connected with one of said change-speed members for sliding it when the rod is moved endwise, another pair of pull-rods disposed parallel to the first, one rod of the latter pair carrying an operating member operatively connected with the other of said change-speed members for sliding it when the rod is moved endwise, means operatively connect-

ing the two rods of one pair at adjacent ends, means operatively connecting the two rods of the other pair at corresponding adjacent ends, so that when one rod of either pair is pulled in one direction the other rod of the same pair is pulled in the reverse direction, a single control member for the pull-rods arranged to selectively impart tensile stress to either of the other adjacent ends of either pair of the said pull-rods, two parallel rocking-levers, the end of one lever having sliding engagement with a pull-rod of one pair, the corresponding end of the other lever having pivotal but non-sliding engagement with the same rod, the opposite end of the first-mentioned lever having pivotal but non-sliding engagement with a rod of the other pair, and the corresponding end of the other lever having sliding engagement with the same rod, the said levers further being so spaced apart that when a pull-rod of one pair is operated one lever is rocked over by means of its engagement with a pull-rod of that pair until its other end butts against that end of the other lever which has non-sliding engagement with a pull-rod of the other pair and thus prevents rocking of that lever in one direction, an arm having two stops spaced apart, said arm being operatively connected to one of said change-speed members, the said stops being located on opposite sides of the operating member movable with the other change-speed member and so spaced that when the latter change-speed member is at one end of its travel its operating member lies against one of the aforesaid stops and thus prevents the other operating member from moving in one direction and when it is at the other end of its travel it lies against the other stop.

6. In variable-speed gear comprising a plurality of slidable change-speed members, the combination with the change-speed members, of a plurality of pull-rods operatively engaged one with each member to impart sliding movement to their allotted members, a single control-lever pivoted to swing about an axis transverse to its length, said lever having a yieldingly-controlled telescopic extension carrying a lateral pin, an arcuate plate having a series of slots wherein the said pin can be selectively moved by combined swinging and telescopic movement of the lever, and pick-up fingers disposed one in each slot and connected in pairs to the aforesaid rods.

7. In variable-speed gear comprising two slidable change-speed members, the combination with the two change-speed members, of a pair of pull-rods whereof the elements are arranged side-by-side, one rod being operatively connected with one of said members for sliding it when the rod is moved endwise, another pair of pull-rods disposed parallel to the first and having one rod op-

- eratively connected with the other of said members for sliding it when the rod is moved endwise, means operatively connecting the two rods of one pair at adjacent ends, 5 means operatively connecting the two rods of the other pair at the corresponding adjacent ends so that when one rod of either pair is pulled in one direction the other rod is pulled in the reverse direction, a return 10 member disposed transversely to the pull-rods and in the path of the same so that when it is advanced it will move any rod forward which projects relatively to its neighboring rod and thus will return them 15 all to their neutral position, and a single control-member for the pull-rods and for the said return member arranged to selectively operate any one of the pull-rods or the return-member.
- 20 8. In variable-speed gear comprising a slidable gear-shifting member, the combination with the gear-shifting member, of a pull-rod operatively engaged therewith at a point intermediate of its ends, a second pull-rod having one end operatively connected

with one end of the former pull-rod to pull the same in one direction, and a control member arranged to selectively impart tensile stress to the other ends of said pull-rods to slide the gear-shifting member at will in either direction. 30

9. In variable-speed gear comprising a plurality of slidable gear-shifting members, the combination with said members, of a plurality of primary pull-rods operatively connected at points intermediate of their ends each with one gear-shifting member to impart sliding movements to their allotted members, a plurality of secondary pull-rods allotted one to each of said primary pull-rods and having each one end operatively connected to one end of its allotted primary pull-rod to pull the same in one direction, and a single control member for all the pull-rods arranged to selectively impact a tractive force to the other end of each pull-rod to slide the gear-shifting members at will in either direction. 35 40 45

In testimony whereof I affix my signature.
BASIL WALTER BRIDGE PUCKLE.
